(57) **CLAIM**

The ornamental design for a piezoelectric sensor, as shown and described.

DESCRIPTION

FIG. 1 is a perspective view of a piezoelectric sensor showing the top, front and right sides of our new design; and,

FIG. 2 is a perspective view of the piezoelectric sensor showing the bottom, rear and left sides thereof.

The grid lines shown in FIGS. 1 and 2 represent surface texture lines.

1 Claim, 1 Drawing Sheet

FIG. 1

FIG. 2

UNITED STATES PATENT AND TRADEMARK OFFICE
CERTIFICATE OF CORRECTION

PATENT NO. : Des. 489,319 S
APPLICATION NO. : 29/166236
DATED : May 4, 2004
INVENTOR(S) : Mansson et al.

Page 1 of 1

It is certified that error appears in the above-identified patent and that said Letters Patent is hereby corrected as shown below:

In the last sentence of the DESCRIPTION, replace "surface texture lines" with
--surface shading--.

Signed and Sealed this

Twenty-ninth Day of January, 2008
